UNITED STATES PATENT OFFICE.

FRANK A. BROWNE, OF WAYNE, PENNSYLVANIA, ASSIGNOR TO THE BARBER ASPHALT COMPANY, OF PHILADELPHIA, PENNSYLVANIA, A CORPORATION OF VIRGINIA.

ROAD ENGINE.

Application filed August 10, 1921. Serial No. 491,273.

To all whom it may concern:

Be it known that I, FRANK A. BROWNE, a citizen of the United States, residing in Wayne, in the county of Delaware and State 5 of Pennsylvania, have invented certain new and useful Improvements in Road Engines, whereof the following is a specification, reference being had to the accompanying drawings.

10 My invention relates to road engines, and the like, of the class typified by the steam roller and the traction engine. The invention is concerned with propelling and steering mechanism suitable for vehicles of this 15 class, as well as their general construction. I aim to make the engine powerful and rugged in design and construction; and convenient, reliable, and flexible in operation. How these and other advantages can be obtained in connection with my invention will 20 appear from the description hereinafter of the best embodiment of said invention at present known to me.

In the drawings, Fig. I is a side elevation 25 of a steam roller constructed in accordance with my invention.

Fig. II is a plan view of the steam roller shown in Fig. I, with various parts in horizontal section and other parts being 30 omitted to avoid confusion.

Fig. III is a side elevation on a larger scale than Figs. I and II, illustrating the mounting of the driving engine.

Fig. IV is a rear view corresponding to 35 Fig. III, certain parts being broken away or omitted for the sake of clearness of illustration.

As here illustrated, the steam roller road engine comprises a box-like fore and aft 40 frame structure 10 that carries the upright steam boiler and furnace 11 and the driving engine 12; a front steering "truck" 14 consisting of a broad roller 15 mounted on trunnions 16 in a yoke frame 17 which has a 45 vertical trunnion 18 journaled in a bracket 19 attached to the front end of the frame 10; and a pair of wheels 20 (of greater diameter and narrower individual tread than the roller 15) mounted at opposite sides of the 50 frame 10. On the upper end of the steering truck trunnion 18 is keyed a gear sector 21 that meshes with a pinion 22 keyed on the upper end of a short upright shaft 23 journaled in the bracket 19. On the lower end 55 of the shaft 23 is fixed a worm wheel 24

that meshes with a worm 25 fixed on a short transverse steering shaft 26 which is also journaled in the bracket structure 19. By turning the steering shaft 26 one way or the other (as hereinafter described) the truck 14 60 may be turned or swung either way for the purpose of steering the road engine. Moreover, the pitch of the worm 25 is such as to make the steering connections irreversible and self-locking; i. e., no external force acting on the roller 15 (due to the roughness of the ground travelled over, for example) can turn the truck 14 either way so as to alter the course of the road engine. 65

Still referring to Figs. I and II, it will be 70 seen that the main frame 10 comprises fore and aft sidewalls or girders 30 and 31, united at their forward ends by the bracket 19 (whose rear corner flanges 33 are riveted to them), and at their rear ends by the side-tank or bin and cab-floor structure 34, which is secured to them by upright angle-bar clips 35, as well as by the forward ends of 75 fore and aft-channel-bars 36 that help to secure the floor to the tanks. The sides 30 and 31 are also connected and braced together by flange-ended shaft-housings 37, 80 38, and 39, whose functions will be more fully explained hereinafter. The frame side 30 consists of a single, flat plate, while the 85 side 31 is offset inward to afford a gear casting 40 in this side of the frame. As shown, the frame side 31 comprises forward and rear side plates 41 and 42 (the latter extending to a point just forward of the shaft 90 housing 37) and an intermediate side plate 43 connecting them; and it is this intermediate side plate 43 that is set in to form the gear compartment 40. At its front and rear edges, the plate 43 is united to the 95 plates 41 and 42 by interposed upright channel bars 44 with their flanges riveted to said plates. The impairment of girder strength in this side of the frame 10 resulting from this construction is compensated for (in 100 large measure, at least) by fore and aft channel bars 46 with their rear flanges riveted to the upper and lower edges of the plate 43, and by "corner" gusset-plates 47 riveted to the front flanges of the channel 105 bars 44 and 46. The channel bars 44 and 46, it will be seen, form fore and aft and upper and lower walls for the gear compartment 40, while the plate 43 forms its 110 rear wall.

The upright steam boiler and furnace unit 11 is mounted between the side plates 30 and 31 just ahead of the tank and floor structure 34, being supported by downward facing brackets 48 riveted thereto and resting on and bolted to upward-facing brackets 49 riveted to the outer sides of the plates 30 and 31. The steam engine 12 is located between the frame sides 30 and 31 a little forward of the boiler 11, just about abreast of the gear-casing 40. How it is mounted and supported will be described herein-after. In the forward portion of the frame 10, below the engine 12, is mounted a water-tank 50 that not only affords a reserve supply for the boiler 11, but serves as adjustable ballast for securing a proper fore and aft distribution of weight, so as to give the roller 15 and the wheels 20 their proper relative loading. This tank 50 has a covered clean-out manhole 51 in its top, and a drain-plug 52 in its bottom.

The drive wheels 20 are overhung and separately rotatable at the projecting ends of a transverse shaft 54 mounted in the rearmost housing 37, and have driving gears 55 bolted fast to the inner sides of their spokes, adjacent the main frame sides 30 and 31. Preferably, one drive wheel 20 is held fast to the shaft 54 by a key pin 56 in the latter, while the other wheel 20 is ordinarily left free to turn on said shaft 54. Outside the frame 10, overhung on the ends of a transverse countershaft 57 in the housing 38, are pinions 58 and 59 for driving the gears 55 and the drive wheels 20. In the gear casing 40 is a pinion 60 which is fast and overhung on one end of a countershaft 61 in the housing 39, and it is driven by the engine 12 through intermeshing gears 62 and 63 fast and overhung on the projecting ends of the shaft 61 and of the engine crank 65, respectively,—outside the frame 10 on the opposite side thereof from the gear casing 40. The pinion 60 meshes with a gear 66 mounted in the gear casing 40 about the countershaft 61, and through it drives the pinions 58 and 59, the countershaft 57, and the drive-wheels 20.

Preferably, the drive from the gear 66 to the drive wheels 20 is not a hard and fast, rigid one, but allows some relative turning of the drive wheels, so as to enable the engine to take curves more readily. As shown, the connection includes a differential gearing which comprises a bevel gear 67 keyed fast on the countershaft 57, (on whose hub the gear 66 is mounted to revolve) a bevel gear 68 fast to the hub of the pinion 59, and a number of small bevel pinions 69 mounted in openings in the web of the gear 66. The pinion 58 is keyed fast on the shaft 57, while the pinion 59 is loose thereon; and thus these pinions and the drive wheels 20 can turn in opposite directions

relative to one another through rotation of the bevel pinions 69 on their axes independently of the revolution of gear 66 about shaft 57. On occasion, however, the differential can be put out of action and the wheels 20 constrained to turn in unison, by simply inserting a locking pin 70 through a hole in the hub of the loose wheel 20 into one of a number of holes in a disc 71 keyed fast on the shaft 54 between the wheel hub and the adjacent frame side 31. This enables the road engine to start when stopped or "stalled" with one of its wheels 20 in a mud-puddle, for example.

Referring, now, to Figs. III and IV as well as Figs. I and II, it will be seen that the steam engine 12 is a duplex one with double cylinder and valve-chest structure 80 at one end of a common frame and with common crank shaft 65 journalled in two arms 81 at the other end of said frame. The connecting rods 82 from the piston rods of the two cylinders are attached to cranks 83 between the frame arms 81, and the steam-distributing valve rods 84 are actuated through valve-gears of well-known "rod" type from eccentrics 85 outside said frame arms. The reversing arms 86 of the valve gears are fast on a common shaft 87 mounted in bearings on the upper sides of the frame arms 81. This shaft 87 may be rocked to adjust the valve-gear to reverse the engine by means of a reach-rod 88 connected to a crank arm 89 fast to one end of the shaft 87 and extending rearward to any convenient point—such as the engine cab. Steam is supplied from above to the valve-chests 80 through branch pipes 90 from a common centrifugal throttle governor 91 connected to a pipe 92 leading from the top of the boiler 11; and the exhaust steam is led off from the lower sides of the valve chests 80 through a couple of pipes 93 that communicate with said valve-chests through passages in a subjacent transverse header-like structure 94 whose opposite ends are bolted to the valve-chests. As shown, the exhaust pipes 93 lead to nozzles 95 in the conical hood 96 at the base of the boiler smoke-stack 97, so that the exhaust may be utilized to improve the draft. The speed-governor 91 is driven by a belt 98 from a pulley on a fore and aft shaft 99 which is itself driven by bevel gearing 100 from the engine crank-shaft 65.

The forward end of the engine 12 is supported by feet 101 on the frame-arms 81 which rest on and are bolted to flanges 102 that project forward from the shaft-housing 39, one near either end thereof. Like the others (37 and 38), this housing 39 has end flanges 103 that bear against the frame sides 30 and 31 (plate 43) and are bolted or riveted to them. Thus this end of the engine 12 is mounted and supported about 100

the countershaft 61, by means embracing said shaft. The rear end of the engine 12 is pivotally supported from a transverse channel beam 105 connected by bracket clips 106 between the frame sides 30 and 31 (43), by means of a pair of upstanding lugs 107 on said beam and an intervening lug 108, depending from the header 94 and connected to said lugs 105 by a fore and aft pivot pin 109. Thus the engine 12 as a whole has what is virtually a three-point support or "suspension" on the main frame or chassis 10, so that no external strains whatever are imposed on the engine structure either by the working of the chassis on uneven ground or by thermal expansion and contraction of the engine itself.

The steering shaft 26 can be turned to swing the steering truck 14 by means of a fore and aft sectional shaft 110, 111 connected to said shaft 26 by bevel gearing 112 and extending rearward to a steering hand-wheel 113 in the cab. In order to relieve the engineer of the labor of turning the massive steering truck 14 by hand, means are provided for bringing the power of the engine 12 to bear for this purpose. As shown, there is fixed on the end of the engine crank-shaft 65 a bevel gear 115 which meshes with bevel gears 116 and 117 loosely mounted on the forward shaft section 110 at opposite sides of said gear 115, and housed in a casing 118 secured to the frame side 31 over a suitable opening therein. On the shaft 110, between the gears 116 and 117, a centrally grooved double cone friction-clutch member 120 is splined so as to turn with said shaft, though free to shift lengthwise of it. When the clutch member 120 is in the central position shown, its two conical clutch-faces remain midway between corresponding conical clutch recesses in the adjacent sides of the oppositely revolving gears 116 and 117 without contact with either of them, and hence the shaft section 110 remains at rest. The clutch member 120 may, however, be shifted either way along the shaft 110 by a relatively slight turn of the shaft section 111 one way or the other. For this purpose, a bell-crank lever 121 is pivoted on the casing 118 at 122, and its forked end is provided with projections 123 engaged in the groove of the member 120. The other lever arm 124 is pivoted at 125 (as with a pin and slot connection) to a crank-arm 126 normally fast to the shaft section 111, as shown.

For hand steering, the shaft sections 110, 111 may be coupled together to turn as one by forcibly pushing the rear section 111 forward from the position shown in Figs. I and II and then turning it until the front teeth of the clutch member 127 on the section 111 interlock with those of the clutch member 128 on the forward section 110, the

forward end of the section 111 moving and being supported in the bore of the member 128. The forward shift of the clutch member 127 throws its rear teeth out of engagement with those at the forward side of the hub 129 of the power steering crank-arm 126, so that subsequent turning of the rear shaft section 111 does not affect the power steering gear described above. The hub 129 is splined on the shaft section 111, and is kept in a fixed fore and aft position (despite shifting of the shaft 111 longitudinally) by a bracket arm 130 fastened to the upper channel bar 46 and engaged in a circumferential groove in said hub 129.

The fore and aft shifting of the rear shaft section 111 may be controlled by any suitable form of catch or locking device, diagrammatically indicated at 131.

In order to keep the surface of the roller 15 free of adherent material that might prevent it from leaving a perfectly smooth rolled surface, sheet metal scraper blades 132 are pivoted in lugs at front and rear of the yoke 17. The scraper blades 132 are pressed against the roller by a helical tension spring 133 connected between crank arms 134 on the ends of the pivot shafts 135 of the scrapers. For a similar purpose, the drive wheels 20 are provided with scraper blades 136 carried by leaf or flexion springs 137 which are attached to clamps 138 that can be clamped in various angular positions about studs 139 attached to the frame 10. No matter whether the engine is going ahead or is backing, one of the scrapers will act effectively on each of the rollers and wheels 15 and 20.

Over the top of the main frame 10, from the boiler 11 forward to the bracket 19, may be placed a plank or other cover or deck 140, for the convenience of the crew in operating the machine, for the protection of the machinery, and also for use as a convenient platform for articles or material to be transported.

Having thus described my invention, I claim:

1. A road engine comprising a box frame including forward and rear side-sections one of which is provided with a recessed intermediate portion affording a gear casing, and separately rotatable drive wheels at its opposite sides, a transverse countershaft in said frame with a pinion at either end thereof for separately rotating said drive wheels, an engine supported in said box frame by a three-point suspension and having differential connection with said pinions and drive wheels, and an alternative means to lock the drive wheels together for rotation in unison.

2. A road engine comprising a reinforced box frame including forward and rear side sections one of which is interme-

diately recessed to afford a gear casing and separately rotatable drive wheels at its opposite sides, a transverse countershaft journalled in said box frame with an overhung pinion at either end thereof for separately rotating the drive wheels, one of said pinions being fast to said countershaft and the other loose thereon, an engine mounted between the sides of said box frame on two opposed rigid supports and a third pivotal support with a driving connection to the aforesaid pinion including a differential gearing on said shaft adjacent the loose pinion having a gear fast thereto and a gear fast to the shaft, a complementary member secured on the drive shaft and one driving wheel being provided with registerable apertures, and removable means for insertion in the registerable apertures to lock said drive shaft and driving wheel together.

3. A road engine comprising a fore and aft box frame with a gear compartment in one side thereof and drive wheels at its opposite sides; a transverse countershaft in said frame with pinions on its opposite ends, outside said frame, for driving said drive wheels an engine between the sides of said frame; another transverse countershaft in said frame; gearing operatively connecting the engine shaft to said latter countershaft beyond one side of said frame; and gearing in said gear compartment, inside one of the aforesaid drive wheel pinions, for operatively connecting said latter countershaft to that first mentioned and to said drive wheels.

4. A road engine comprising a fore and aft box frame with a gear casing in one side thereof and separately rotatable drive wheels at its opposite sides having driving gears at their inner sides adjacent the frame; a transverse countershaft in said frame with overhung driving pinions for said driving gears on its outer ends, one beyond said gear casing loose on the shaft; an engine on said frame and a pinion driven thereby in said gear casing; and a differential drive in said gear casing, between its inner wall and said loose pinion, including a driving gear in mesh with said engine-driven pinion and gears actuated thereby to drive said loose pinion and said countershaft.

5. A road engine comprising a fore and aft frame with a steering truck at one end and separately rotatable drive wheels at its opposite sides; a transverse counter-shaft in said frame with means thereon for separately driving said drive wheels, including a differential at one side of said frame adjacent one of them; an engine between the sides of said frame; another countershaft in said frame for driving said differential geared to the engine shaft outside of said

frame on the side thereof opposite said differential; and means outside said frame, on the same side as said differential, for turning said steering truck, said means being operatively connected with one of the shafts 70 last mentioned.

6. A road engine comprising a box frame including forward and rear side sections one of which is intermediately recessed to afford a gear casing and separately rotatable drive wheels at opposed sides thereof, a transverse countershaft in said box frame with an overhung pinion at either end thereof for separately rotating the drive wheels, one of said pinions being fast on said countershaft 75 and the other loose thereon, an engine mounted between the sides of said box frame on opposed rigid supports and a third forwardly positioned fore and aft pivotal support, said engine having a driving connection to said pinion including the differential gearing on said shaft adjacent the loose pinion having a gear fast thereto and a gear fast to the shaft, a complementary 80 disk member secured on the drive wheel shaft and the adjacent drive wheel being provided with registerable apertures, and a pin for insertion through the registerable apertures to lock said drive shaft 85 and driving wheel together.

7. A road engine comprising a box frame including forward and rear side sections one of which is intermediately recessed to afford a gear casing, said box frame having its forward portion isolated by partitions to define a ballast chamber, separately rotatable drive wheels on a common shaft at opposed sides of said box frame, a transverse countershaft in the box frame with an overhung pinion at either end thereof for separately 100 rotating the drive wheels, one of said pinions being fast on said countershaft and the other loose thereon, an engine mounted between the sides of said box frame on opposed rigid supports and a third forwardly positioned fore and aft pivotal support, said engine having driving connection to said pinion including the differential gearing on 105 said shaft adjacent the loose pinion having the gear shaft thereto and a gear fast to the shaft, a complementary disk member secured on the drive wheel shaft and the adjacent drive wheel each being provided with registerable apertures, and a pin for 110 insertion through the registerable apertures to lock the drive shaft and driving wheel together.

In testimony whereof, I have hereunto signed my name at Philadelphia, Pennsylvania, this fourth day of August, 1921.

FRANK A. BROWNE.
